UNITED STATES PATENT OFFICE.

JOHN W. WIHLBORG, OF CHICAGO, ILLINOIS.

POWER MECHANISM.

No. 813,757.

Specification of Letters Patent.

Patented Feb. 27, 1906.

Application filed March 23, 1905. Serial No. 251,611.

To all whom it may concern:

Be it known that I, JOHN W. WIHLBORG, a subject of the King of Sweden and Norway, residing at Chicago, in the county of Cook and State of Illinois, have invented new and useful Improvements in Power Mechanism, of which the following is a specification.

This invention relates to devices for transmitting motion from treadles to a shaft; and the object of the invention is to provide an improved and easy-running connection for that purpose.

In the accompanying drawings, Figure 1 is a sectional plan view of the treadles and the connections to the drive-shaft. Fig. 2 is a horizontal sectional view of the grip mechanism. Fig. 3 is a side view, partly in section, showing the clutch or grip mechanism and bearings on the main shaft. Fig. 4 is a view similar to Fig. 3 with the parts in different positions. Fig. 5 is a view of a modification, showing a more direct connection between the treadles and the grip mechanism.

Referring specifically to the drawings, A indicates the usual stationary frame or iron supports for a sewing or other machine.

B is the cross-bar on which the treadles run. These treadles C and D are mounted upon sleeves C' and D', respectively, upon the bar B, and these sleeves are supported on ball-bearings b and b', respectively. The cone of the bearing b' backs against the treadle C, and the treadles are thus spaced apart. One sleeve is arranged within the other, as shown. Thus the sleeve C' of the treadle C extends through the sleeve D' of the treadle D, the ball-bearings b supporting the sleeve C' upon the rod B and the ball-bearings b' supporting the sleeve D' upon the sleeve C'.

At one end the sleeve C' carries a rigid arm C², located conveniently beside an arm D², projecting from the treadle D, bringing the connecting-rods c and d, by which the motion is communicated, to one side of the machine.

The connecting-rods c and d, referred to, are pivotally attached at one end, as at X, to the treadle-arms and at the other end are connected to the clutch mechanisms, (indicated at G and F, respectively,) operating to drive the shaft J, which carries a fly-wheel H and is supported in bearings I on the frame of the machine. The end of each rod c and d is shaped to form one of a pair of arms f, the

other, f², of which is pivoted thereto by a bolt m, held by a nut m'.

Each of the arms f is connected by a ball-bearing joint at f³ with a projection f⁵, extending from a circular housing L, which extends around the drive-shaft J, and each of the arms f² is similarly connected to a projection f⁶, extending from a similar housing. The housing L incloses blocks k⁵, which cause the balls k² to engage the shaft J when the housing is turned in one direction by means of the interior lugs or shoulders l, which press the springs k⁴ against said blocks and cause them to force the balls k² in the narrow or reduced end of the recesses l', which are formed within the housing around said shaft.

When the rod c or d is thrust out, it spreads the arms f f², as indicated in Fig. 3, and when it is pulled in the other direction it draws the arms together, as indicated in Fig. 4. The clutches carried by the respective arms operate oppositely, so that one takes on the thrust and the other on the pull, and the shaft is intermittently gripped and is caused to rotate always in the same direction. Rubber cushions (indicated at Z) are interposed between the arms to deaden the noise of their coming together.

In the modification shown in Fig. 5 the arms f' are connected directly to the treadles, as by a pivot at y, and will be found serviceable under some conditions.

The clutches connected to each treadle are independently operated. Consequently either one or both treadles may be used; also, since the clutches do not grip except when the treadle is moved either one or both treadles may be held still and the shaft will continue to rotate.

What I claim as new, and desire to secure by Letters Patent, is—

The combination with a treadle, of a connecting-rod pivotally connected at one end thereto and shaped at the other end to form one of a pair of arms, the other arm of said pair hinged to said rod, a shaft, and clutch connections between the arms and the shaft.

In testimony whereof I have signed my name to this specification in the presence of two subscribing witnesses.

JOHN W. WIHLBORG.
